UNITED STATES PATENT OFFICE.

DAVID C. WALTER, OF TOLEDO, OHIO.

FEED-WATER REGULATOR.

SPECIFICATION forming part of Letters Patent No. 294,705, dated March 4, 1884.

Application filed April 27, 1883. (No model.)

To all whom it may concern:

Be it known that I, DAVID C. WALTER, a citizen of the United States, residing at Toledo, in the county of Lucas and State of Ohio, 5 have invented a new and useful Feed-Water Regulator for Steam-Boilers, of which the following is a specification.

My invention relates to improvements in feed-water regulators for steam-boilers, in 10 which is placed, in close proximity to the boiler, an upright cylindrical chamber containing a float operating a valve delivering steam to a positive-acting steam feed-pump; and the objects of my improvements are, first, to keep 15 water in the boiler to its proper height; second, to provide means whereby steam is delivered to the steam feed-pump direct from the boiler, the object being to avoid creating a reduction of pressure in the float-chamber, 20 which causes the water in said chamber to rise above the water in the boiler, thereby closing the valve before the proper time; third, of an overflow-pipe placed just above the water-line. In case the water rises in the 25 chamber above the proper height it will flow through said pipe back into the boiler, thus preventing the float from rising too high. I attain these objects by the mechanism illustrated in the accompanying drawings, in 30 which—

Figure 1 is a side view of my improvement attached to a boiler. In this view a portion of the chamber is broken away, showing the location of the valve-arm and its connecting- 35 rods. Fig. 2 is a detailed view of the chamber, float and valve, and balance-rod and ball.

Similar letters refer to similar parts throughout the several views.

In Fig. 1, A is an upright cylindrical chamber containing a float, *h*, (cylindrical in form,) the chamber A communicating with the steam and water spaces of the boiler by the pipes *c*, *n*, and *d*.

e represents a valve-casing extended from 45 and opening into the upper portion of the float-chamber. The valve in casing *e* is connected to the float *h* in said chamber by the valve-arm *f* and connecting-rod *g*. The float is weighted at the lower end with heavy suitable material, to keep it in a vertical position and give it weight sufficient to move the valve.

In Fig. 2, *a'* is a taper valve with upper and lower wings. As the float descends, the lower wing, *a''*, passes the steam-port of valve-chamber and delivers steam to the steam feed-pump 55 through pipe *b*. The valve-chamber receives steam direct from the boiler through the pipe *b'*. The back end of the valve at *a''* forms a steam-tight wall between the valve and float chamber, thus preventing the escape of steam 60 from said chamber, the object being to prevent any reduction of pressure in the float-chamber.

In Fig. 2 the valve-shaft *m'* extends through the casing of the float-chamber, the float being connected to the shaft *m'* in the manner shown at *a''* by the valve-arm *f* and connecting-rod *g*.

e' is a portion of the valve-chamber extending from and into the chamber leading to the 70 cylindrical float-chamber. The opposite end of the valve-shaft extends through a metallic stuffing-box, *J*, which, being screwed in against a shoulder on the valve-shaft, forms a steam-tight joint, and also takes up the wear of the 75 valve.

b'' is a knob secured to the outer end of the shaft *m*.

O is a balance-rod passed through an opening in said knob at right angles to the shaft *m*. 80

P is a weight secured to one end of the rod *O*. By shifting this rod from one side to another the valve may be regulated without reference to the float.

l is a steam-whistle placed above the upper 85 wing of the valve.

In case the water in the boiler gets too low the upper wing of the valve passes the port, giving steam to the whistle, thus giving low-water alarm. The reverse of this movement 90 gives alarm for too much water.

The pipe *n* is situated just above the water-line, between the float-chamber and boiler, and in case of any reduction of pressure in the chamber the water will flow back into the 95 boiler and prevent the float from rising.

I claim—

In a boiler-feeder substantially as described and shown, the combination of the boiler, the float-chamber arranged alongside of and connected with the boiler by steam and water pipes, the float, the valve-chamber connected 100

by suitable pipes with pumping-engine and supported on and opening into the float-chamber, the steam-pipe connecting the boiler and the valve-chamber, and the rotary valve connected with the float and provided with ports adapted to register with the pumping-engine pipes, and connected with and rotated by the float, said valve being provided on its inner end with plate a° , serving as a partition be-

tween the valve and float chamber, whereby to the steam is passed direct from the boiler to the pumping - engine, substantially as described, and for the purposes specified.

DAVID C. WALTER.
